UNITED STATES PATENT OFFICE.

GEORGE OWEN FISHER, OF BROOKLYN, NEW YORK; BESSIE M. FISHER ADMINISTRATRIX OF SAID GEORGE OWEN FISHER, DECEASED, ASSIGNOR TO BESSIE M. FISHER, OF BROOKLYN, NEW YORK.

AUTOMATIC GUN.

Application filed November 5, 1920. Serial No. 421,917.

To all whom it may concern:

Be it known that I, GEORGE OWEN FISHER, a citizen of the United States, residing at Brooklyn, in the county of Kings and State of New York, have invented certain new and useful Improvements in Automatic Guns, of which the following is a specification.

This invention relates to firearms of the automatic or "machine gun" type.

The objects of the invention are to provide simple, practical and reliable mechanism for converting such guns at will from automatic to single shot operation.

15 A special object is to make this control mechanism applicable to an approved and tried rapid fire gun which is now in use.

In the drawings accompanying and forming a part of this specification, I have disclosed the invention as applied to the type of gun referred to, but wish it understood that the invention is not limited to this particular use or to the particular structure shown, as will be clear from the scope of the 25 following specification and claims.

Figure 1 in the drawings referred to, is a side elevation of an automatic rifle, having the invention incorporated in and forming a part thereof.

30 Figure 2 is an enlarged broken sectional and side elevation of the breech and trigger mechanism, illustrating the parts as set for automatic operation, and showing the automatic magazine trip as about to operate the mechanism for disconnecting the trigger from the sear.

Figure 3 is a similar view, showing the connector as operated on the discharge of the last cartridge from the magazine to uncouple 40 the trigger from the sear. In both Figures 2 and 3 the positioning bolt forming a part of my invention is shown in its inoperative position.

Figure 4 is a view similar to Figure 2, 45 but showing the positioning bolt or change device as turned to position the connector for single fire operation. In this view, the trigger is shown as having been pulled far enough to almost release the sear from the bolt, and the connector as standing ready to clear the sear immediately the bolt is released.

Figure 5 is a broken side elevation of

parts as they appear in Figure 4, but with the trigger unpressed. 55

Figure 6 is a detached detail view of the turn bolt which controls the fire.

Figure 7 is a broken sectional view, as taken on substantially the plane of line 7-7 of Figure 5, with the turn bolt standing in 60 the inoperative dotted line position shown in that view.

In the construction illustrated, the bolt of the gun is shown in a general way at 10, it being provided as customary with a notch 11 65 for the heel of the sear 12. This sear is shown as pivoted at 13 and as acted on by a spring 14 which tends to thrust it into holding engagement with the bolt.

The trigger of the gun is indicated at 15, 70 and is shown as pivoted at 16. The finger portion of the trigger is thrust downward into the position shown in full lines in Figure 2 by a spring 17 acting on the forwardly extended end of the trigger body. 75

The trigger is coupled to the sear by a connector pivoted at 18 on the rearward portion of the trigger and having a rearwardly extending arm, 19 for engagement with the forward end of the sear and a forwardly and upwardly extending arm 20 for engagement by a trip lever. The forward arm of this connector is acted on by a spring 21 which rocks the connector rearwardly, so as to position the arm 19 beneath the toe of 85 the sear.

The trip lever is illustrated in the form of a yoke 22 surrounding the upper body portion of the trigger and pivotally supported on the pivot pin 16 of the trigger. A lug 90 or shoulder 23 on the rearward end of the trip lever overstands the arm 20 of the connector and at its forward end the trip lever is provided with an extension 24 for engagement by a trip lug 25 carried by the spring-pressed cartridge feed plunger 26 of the magazine 27. 95

The described arrangement and proportion of parts is such that when the trigger is pulled and held back, as indicated in the 100 dotted lines in Figure 2, the sear will be retracted from engagement with the bolt, and the gun will then fire automatically, the bolt reciprocating under the alternate impulses of the expanding gases and the return spring 105 to eject the empty shells and to carry the

fresh cartridges from the magazine into the barrel and fire them. This automatic firing, of course, is under absolute control of the trigger because if at any time pressure on the trigger is released, the sear will immediately snap back into holding engagement with the bolt. As the last cartridge leaves the magazine, the trip lug 25 of the magazine feed engages the forward extension of the trip lever, rocking the forward end of the same upwardly and the rearward end of the same downwardly, as in Figure 3, so as to rock the connector forwardly and thereby disengage the arm 19 of the same from holding engagement with the sear. This frees the sear of the trigger control and causes it to snap into holding engagement with the bolt as soon as the last cartridge is fired.

The present invention may be said to consist in positioning the trip lever at an intermediate point between the two extremes shown in Figures 2 and 3 so as to cause said trip lever, when the trigger is actuated, to position the connector so that said connector after releasing the sear will immediately clear the same, and permit the sear to spring back into holding engagement with the bolt. This intermediate position I have illustrated in Figure 4, and the means for accomplishing this end I have shown in the form of a turn bolt 28 rotatably supported beneath the forward extension of the trip lever, and having a shoulder which, when the bolt is turned as in Figure 4, will lift the forward end of the trip lever to a position where the rearward end of the lever will slightly depress the forward end of the connector when the trigger is pulled. This in effect shortens the hold of the connector on the sear so that immediately after the sear is released from the bolt, the point of the connector will slide free of the point of the sear so as to release the sear and permit it to immediately snap back into engagement with the bolt on its recoil stroke or into the position shown in Figure 3.

The turn bolt which constitutes in effect a "change device" is provided with a flat part 29 on one side thereof which, when the bolt stands in the position shown in Figures 2 and 3, allows clearance for the forward end of the trip lever, thereby making the turn bolt ineffective.

The turn bolt is actuated, in the illustration, by a lever 30 on the outer end thereof, which carries a spring-pressed pin 31 for restraining the bolt in either of the positions described.

The invention, it will be seen, provides a simple and at the same time a dependable device which may be readily applied to guns of the type shown and without necessitating any material alterations or changes.

One of the special advantages of the in-

vention is that this device does not in any material sense affect the trigger tension, the gun being operable practically with the same touch for either automatic or single shot work.

What I claim is:

1. In a gun of the character described, a bolt, a sear for cooperation therewith, a trigger, a connector pivotally mounted on the trigger and engageable at one end with the sear, a trip lever for engaging and positioning the connector, and means for positioning said trip lever to govern the period of engagement of said connector with the sear during the operation of said trigger. 70

2. In a gun of the character described, a trigger, a sear, a connector pivotally mounted on the trigger and traveling bodily therewith, a trip lever pivoted concentrically with respect to the trigger and having a portion to engage and shift the connector about its pivotal point thereby governing the period of engagement of said connector with the sear during the operation of said trigger. 80

3. In a gun of the character described, a trigger a sear, a connector pivotally mounted on the trigger and traveling bodily therewith, a trip lever pivoted concentrically with respect to the trigger and having a portion to engage and shift the connector during the trigger movement, and means for positioning said lever to cause the connector to actuate and to then immediately clear the sear, the said positioning means including a turn bolt standing in the plane of the trip lever and having a flattened side rendering said bolt inoperative when turned toward the trip lever. 90

4. In a gun of the character described, a pivoted trigger, a pivoted connector carried thereby, a bolt, a sear for holding the same and arranged for engagement by the connector, a trip lever pivoted concentrically with respect to the trigger and engaging at one end the connector for positioning the same with respect to the sear, and means for engagement with the opposite end of said trip lever to enable continuous engagement of the connector with the sear or to effect disengagement of the connector from the sear after each actuation thereof. 105

5. In a gun of the character described, a bolt, a sear for holding the same, a trigger, a connector interposed between the trigger and sear, a trip lever controlling the position of said connector, a magazine including a movable stop for automatically actuating the trip lever, and means for positioning said trip lever independently of said automatic stop. 110

6. In a gun of the character described, a bolt, a sear for holding the same, a trigger, a connector interposed between the trigger and sear, a trip lever controlling the position 125

of said connector, a magazine including a movable stop for automatically actuating the trip lever, and means for positioning said trip lever independently of said automatic stop, and including a turn bolt having relatively high and low portions adapted to be positioned in line with a part of the trip lever.

7. In a gun of the character described, a bolt, a sear for holding the same, a pivoted trigger, a connector pivotally carried by said trigger, a trip lever mounted on the trigger pivot and having one end overstanding a part of the connector and its opposite end extending beyond the trigger, and a positioning member beneath said extended end and having a shoulder adapted to engage the same.

8. In a gun of the character described, a bolt, a sear for holding the same, a pivoted trigger, a connector pivotally carried by said trigger, a trip lever mounted on the trigger pivot and having one end overstanding a part of the connector and its opposite end extending beyond the trigger, and a posi-

tioning member beneath said extended end and having a shoulder adapted to engage the same, said positioning member being in the form of a rotatable bolt having one of its sides flattened to stand free of the extended end of the trip lever.

9. In a gun of the character described, a bolt, a sear for holding the same, a pivoted trigger, a connector pivotally carried by said trigger, a trip lever mounted on the trigger pivot and having one end overstanding a part of the connector and its opposite end extending beyond the trigger, a positioning member beneath said extended end and having a shoulder adapted to engage the same, said positioning member being in the form of a rotatable bolt having one of its sides flattened to stand free of the extended end of the trip lever, and means automatically actuated in the operation of the gun to rock the trip lever independently of the positioning means aforesaid.

In testimony whereof I affix my signature.

GEORGE OWEN FISHER.
